UNITED STATES PATENT OFFICE.

WILLIAM L. ANDERSON, OF CINCINNATI, OHIO.

COMB.

1,233,956.

Specification of Letters Patent. Patented July 17, 1917.

Application filed May 21, 1917. Serial No. 170,020.

To all whom it may concern:

Be it known that I, WILLIAM L. ANDERSON, a citizen of the United States, residing at Cincinnati, in the county of Hamilton 5 and State of Ohio, have invented certain new and useful Improvements in Combs; and I do declare the following to be a full, clear, and exact description of the invention, such as will enable others skilled in the art 10 to which it appertains to make and use the same.

My invention relates to improvements in combs and more particularly to that type of comb adapted for use in drying, straightening and smoothing the hair.

The primary object of the invention is to provide a comb of this character in which the pressure of the heated teeth on the strands of hair may be positively controlled 20 by means of an adjusting screw.

Another object is to provide a device of this character formed from a heat conducting material adapted to retain the heat for a long period of time.

25 Another object is to provide a device of this character having movable teeth so arranged as to prevent catching and breaking off of the hair while operating the comb.

With these and numerous other objects in 30 view, my invention resides in the novel features of construction and the combination and arrangement of the several parts as will be hereinafter described in the specification and claims and illustrated in the accompanying drawings in which:

Figure 1 is a side elevation of an improved comb;

Fig. 2 is a top plan view thereof;

40 Figs. 3 and 4 are longitudinal sections with parts in elevation showing two different positions of parts; and,

Fig. 5 is a detail transverse section on the plane of the line 5—5 of Fig. 3.

45 Similar reference numerals are employed to indicate corresponding parts throughout the several views.

The present embodiment of my invention as illustrated in the accompanying drawings comprises an elongated back 1 formed 50 of any suitable heat conducting material and having a longitudinal recess 2 in its upper wall or face, said back being provided at its inner end with a suitable handle 3 and ferrule 4. Formed integral with and depending from the lower wall or face 1 of the back 55 is a plurality of parallel stationary teeth 5.

The recess 2 is provided in its bottom with a series of openings which are disposed between the stationary teeth 5 for a purpose to be hereinafter set forth. The recess 2 is 60 provided adjacent its inner end with a longitudinal slot 6 which opens through the lower wall of the back 1, said slot being so disposed as to receive the short end 7 of an operating lever 8 which is fulcrumed adjacent its inner end between a pair of depending apertured ears 9, and whose purpose will be hereinafter set forth.

Disposed in the recess 2 is an elongated bar 10 having teeth 11 adapted to project 70 through the openings between the stationary teeth 5, said bar and teeth being movable longitudinally of said back. The bar 10 is provided in its lower face adjacent its inner end with a transverse notch 12 which is 75 adapted to receive the inner short end 7 of the operating lever 8. The outer end of the bar 10 is provided with a longitudinally extending threaded socket 13 which is aligned with an aperture 14 in the outer end of the 80 recess 2 and for a purpose to be set forth.

Upon pressing the lever 8 inwardly toward the handle 3, the short end 7 of the lever will force the bar 10 outwardly and thereby move the teeth 11 which are disposed 85 between the stationary teeth 5 and for the purpose of returning the movable teeth to their former positions, a spring 15 which in this instance is in the form of an elongated flat strip, is adapted to have one end secured 90 beneath the ferrule 4 and to have its other end contacting with the inner face of the lever 8, the tendency being to force the lever outwardly, thereby moving the teeth 11 inwardly.

95 For the purpose of limiting the inward movement of the teeth 11 under the action of the spring 15, a set screw 16 is inserted in the aperture 14 in the end of the back 1 and is threaded into the socket 13 in the 100 outer end of the movable bar 10. The aperture 14 is provided with a shoulder 14' which engages the head of the set screw to limit the inward movement thereof. It will be readily seen that the adjustment of the 105 set screw will positively control the inward movement of the teeth 11, thereby controlling the pressure of the teeth upon the strands of hair.

110 In operation, the comb is heated by any suitable means and in drying, straightening or smoothing the hair, the set screw 16 is

first adjusted and the lever 8 pressed inwardly to space apart the teeth and the comb is then placed in operative position, the strands of hair being disposed between 5 the stationary and movable teeth and the lever is then released and is forced outwardly under the pressure of the spring 15. When the lever is pushed outwardly as above stated, the movable bar 10 will be 10 shifted inwardly and the teeth will press against the strands of hair, and as the comb is drawn through the hair, said strands will be dried and straightened. It is readily seen that the set screw can be adjusted to regulate the pressure of the teeth upon the hair so as to prevent breaking of the strands and at the same time thoroughly dry the same.

From the foregoing description, taken in connection with the accompanying drawings, the construction and operation of my 20 improved comb will be readily understood, but it is also to be understood that within the scope of the invention as claimed, numerous changes may be made without sacrificing 25 the principal advantages.

I claim:—

1. A comb of the class described including a back, a plurality of parallel stationary teeth on said back, a plurality of movable 30 teeth between said stationary teeth, means for positively shifting said movable teeth in one direction, a spring for shifting said teeth in the opposite direction, and adjustable means for limiting the movement of 35 said movable teeth by the spring.

2. A comb of the class described including a hollow back, a plurality of parallel stationary teeth on said back, a movable bar in said back, a plurality of movable teeth 40 on said bar, said teeth being disposed between the stationary teeth, means for positively shifting said bar and movable teeth in one direction, a spring for shifting said teeth in the opposite direction, and an adjustable screw in said bar and engaged with 45 said back to limit the movement of said bar and the movable teeth by the spring.

3. A comb of the class described includ-

ing a hollow back, a cover for said back, a plurality of parallel stationary teeth on said 50 back, a movable bar in said back, a plurality of parallel movable teeth between and coextensive with said stationary teeth, said movable teeth being formed integral with said bar, means for positively shifting said 55 bar and movable teeth in one direction, a spring for shifting said bar and movable teeth in the opposite direction, and adjustable means for limiting the movement of said bar and movable teeth by the spring. 60

4. A comb of the class described comprising an elongated back having a longitudinal recess in its upper wall, a cover for said recess, a handle on the inner end of said back, a plurality of parallel stationary teeth on 65 the lower side of said back, said recess being provided with openings between said teeth, a movable bar in said recess, parallel and movable teeth on said bar, said movable teeth being disposed in said openings between the stationary teeth, said back being provided with a longitudinal aperture in its outer end, said bar having a threaded socket aligned with said aperture, said back having a longitudinal slot in its bottom near 70 its inner end, a lever fulcrumed adjacent one end to said back and having its short end projecting through said slot, said bar having a transverse notch in its lower face adjacent its inner end to receive the short 75 end of said lever, said lever being adapted to be pressed to shift the bars and movable teeth in one direction, a spring adapted to force the lever outwardly and shift the 80 movable teeth in the opposite direction, and an adjustable set screw in said aperture and socket to limit the movement of said bar and movable teeth by the spring. 85

In testimony whereof I have hereunto set my hand in the presence of two subscribing 90 witnesses.

WILLIAM L. ANDERSON.
